UNITED STATES PATENT OFFICE

163,487

T FITTING

Edward H. Schustack, Los Angeles, Calif.

Application September 30, 1950, Serial No. 12,413

Term of patent 14 years

(Cl. D91—3)

To all whom it may concern:

Be it known that I, Edward H. Schustack, a citizen of the United States, residing in Los Angeles, in the county of Los Angeles and State of California, have invented a new, original, and ornamental Design for a T Fitting, of which the following is a specification, reference being had to the accompanying drawing, forming part thereof:

Fig. 1 is a top plan view of a T fitting, showing my new design.

Fig. 2 is a side elevational view thereof.

Fig. 3 is a front elevational view.

I claim:

The ornamental design for a T fitting, substantially as shown.

EDWARD H. SCHUSTACK.
